(57) **CLAIM**

The ornamental design for a fence post extension, as shown and described.

DESCRIPTION

FIG. 1 is a first perspective view of a fence post extension showing the new design;

FIG. 2 is a second perspective view thereof;

FIG. 3 is a front elevation view thereof, the back elevation view being a mirror image;

FIG. 4 is a left-side elevation view thereof, the right-side elevation view being a mirror image;

FIG. 5 is a top plan view thereof;

FIG. 6 is a bottom plan view thereof;

FIG. 7 is a third perspective view thereof;

FIG. 8 is a fourth perspective view thereof;

FIG. 9 is a fifth perspective view thereof; and,

FIG. 10 is a sixth perspective view thereof.

The broken lines in the drawing depict portions of the fence post extension that form no part of the claimed design.

1 Claim, 9 Drawing Sheets
